(57) **CLAIM**

The ornamental design for a refill unit for a dispenser, as shown and described.

DESCRIPTION

FIG. 1 is a perspective view of a refill unit for a dispenser of the new design with a touch-free dispenser shown in dashed lines to show the environment;

FIG. 2 is a perspective view of a refill unit for a dispenser of the new design;

FIG. 3 is a front elevational view of the refill unit for a dispenser of FIG. 1;

FIG. 4 is a side elevational view of the refill unit for a dispenser of FIG. 1;

FIG. 5 is a top plan view of the refill unit for a dispenser of FIG. 1; and,

FIG. 6 is a bottom view of the refill unit for a dispenser of FIG. 1.

The broken lines shown in the Figures represent environment and portions of the refill unit for a dispenser that form no part of the claimed design.

1 Claim, 4 Drawing Sheets
